UNITED STATES PATENT OFFICE.

FRANCIS ROBINIUS, OF INDIANAPOLIS, INDIANA.

COMBINED SWING AND CHAIR.

SPECIFICATION forming part of Letters Patent No. 295,946, dated April 1, 1884.

Application filed January 17, 1884. (No model.)

To all whom it may concern:

Be it known that I, FRANCIS ROBINIUS, a citizen of the United States, residing at Indianapolis, in the county of Marion and State 5 of Indiana, have invented a new and useful Improved Combined Swing and Chair, of which the following is a specification.

My invention relates to an improved reclining-chair having folding legs, and adapted 10 to be supported on swinging cords or to stand upon its legs.

The objects of my improvements are, first, to support the hinged back in a novel and more safe manner than heretofore; second, to 15 provide improved means for attaching the swinging cords to the chair.

The accompanying drawings illustrate my invention.

Figure 1 is a side elevation, showing the 20 device as a swing. Fig. 2 is a plan with the suspending-cords removed. Fig. 3 is a rear elevation of the device as a chair.

a is a rectangular seat, to each side of which is pivoted, near the front edge, an upright, *b*, 25 which extends above the seat to support an arm, *c*, and below the seat to support a foot-rest, *d*. To each side of the seat, near the back edge, is pivoted an upright, *e*, to which the back of the chair is secured. Arms *c* are 30 pivoted to the uprights *b* and *e*, and at a short distance below each arm is pivoted a parallel bar, *f*.

g and *h* are light bars of metal, provided 35 at each end with an upturned eye, *i*, and secured to the under side of the seat, and projecting therefrom on each side. Said bars are for the purpose of forming points of attachment for the suspending-cords *j* *k*, (there being a pair of each,) and are each curved toward and beyond the edge of the seat, so that 40 the points of attachment of the cords may be wide apart. The suspending-cords are removably connected with the eyes *i* by snap-hooks *l*.

45 In this class of swinging chairs as heretofore constructed, the hinged back has been supported at different inclinations by a ratchet-bar pivoted to the back and engaging a pin projecting from the seat, and the back has 50 been supported at the extreme limit of its backward movement by a third cord running from the point of suspension to the back of

the chair, and hanging slack when the back was not fully extended. The ratchet-bar is found to be not well adapted for use by 55 children, for whom the chair is intended, and is liable to give away suddenly. The supporting-cord becoming stretched allows the back to fall too far. For the purpose of avoiding these difficulties, I support the hinged back 60 at different inclinations by passing the rear suspending-cords through eyebolts *m*, secured to the outside of each of the uprights *e*, and thence downward to the hooks *l*, engaging the rear bar, *h* *h*, allowing the said cord to slip 65 freely through said eyebolts *m*. By this construction the back will be sustained at varying degrees of inclination, dependent on the relative distribution of the weight of the occupant of the chair between the seat and the 70 hinged back.

For the purpose of preventing the back from falling too far, I pivot the bars *f* to the uprights at such a distance below the arms *c* that the upper edge thereof and the lower edge 75 of the arm will come together when the back has fallen to its lowest desirable limit, thus furnishing a positive stop, which is not dependent on the attention of the occupant of the chair for its operation. 80

For the purpose of supporting the chair independently of the cords, I hinge to the under side of the seat two pairs of legs, *n* *o*, which are adapted to fold against the bottom, and are supported when extended by brace-hooks *p*. 85

I claim as my invention—

1. The combination, with a folding reclining-chair having a hinged back and cords for suspending the same, of two eyebolts secured to opposite edges of said back, and two of the 90 said suspending-cords passing through said eyes, arranged to slide therein, and attached to a fixed support on the seat of the chair, all substantially as and for the purpose specified.

2. In a folding reclining-chair, the combination, with seat *a*, uprights *b* and *e*, pivoted thereto, as described, and arm *c*, pivoted to said uprights, of bar *f*, also pivoted to said uprights, substantially as and for the purpose specified. 95

FRANCIS ROBINIUS.
